GARTER FASTENER

Elmer J. Schuhmacher, Waterloo, Iowa

Application May 15, 1936, Serial No. 79,967

3 Claims. (Cl. 24—243)

My invention relates to stocking supporting devices, and has among its objects and advantages the provision of an improved fastener for garters.

In the accompanying drawing:

5 Fig. 1 is a view illustrating a fastener attached to a stocking;

Fig. 2 is a sectional view along the line 2—2 of Fig. 1;

10 Fig. 3 is a sectional view along the line 3—3 of Fig. 2; and

Fig. 4 is a perspective view of the clamp parts in separated relation.

In the embodiment selected to illustrate my invention, I make use of a fastener 10 including 15 two grip parts 12 and 14. These parts co-operate for connection with a stocking 16. The part 12 includes a wide portion 18 connected with a stocking engaging part 20 through the medium of a neck 22. The part 20 includes a flange 24 20 for the reception of the wide end 26 of the part 14. The upper end of the part 14 is wider than the neck 28, and the end 26 is of the same width as the part 20. The flange 24 is arranged in spaced relation with the part 20 to provide a 25 trough or abutment 25 (see Fig. 2) within which the end 26 is positioned when the fastener is attached to the stocking.

The grip parts 12 and 14 are secured together by means of a conventional snap fastener 30. 30 Each of the parts 12 and 14 includes a slot 32 and 34, respectively. An elastic strap 36 comprising a part of the garter is threaded through the slots 32 and 34 and the strap is looped as at 38 for connecting purposes.

35 In operation, the wide end 20 of the part 12 is passed underneath the stocking 16 and the wide end 26 of the part 14 is pressed into the trough formed by the part 20 and the flange 24. The two parts are then connected together by the snap fastener 30, at which time the stocking is effectively pinched within the trough. Referring to Fig. 2, it will be noted that the part 14 is slightly bowed at 40. The part 14 is bowed or buckled when the snap fastener is connected, which bowing causes the stocking to be effectively pinched within the trough 25 as indicated at 42.

The parts 20 and 26 are of such width as to pinch a wide area of the stocking, thereby distributing the connection between the fastener and 50 the stocking over a wide area. In this way, I eliminate localization of forces incident to conventional fasteners which tend to tear the stocking. In Fig. 3, I illustrate the wide parts 20 and 26 as being curved to conform to the leg of the wearer.

When the parts 12 and 14 are connected together by the snap fastener 30, the slot 32 is positioned below the slot 34. In this way, the load 55 carried by the garter is transferred to the part

12 so that no pull is applied to the part 14. This arrangement prevents any pull from being transferred to the part 14.

The ends of the flange 24 are curved at 44 to preventing puncture of the stocking. The parts 5 12 and 14 are easily separated because of the shape of the two parts. The neck 22 is narrower than the neck 28 in the area 46, while the area 18 of the part 12 is wider than the part 14 at that point. In operating the two parts, the area 18 10 may be supported with one hand, while the projecting area 46 permits the part 14 to be grasped to facilitate disconnection of the fastener 30.

The parts 12 and 14 may be made of any suitable material. I have attained good results with 15 Celluloid. Buckling of the part 14, as at 40, provides an effective holding function for that portion of the stocking pinched within the trough 25.

Without further elaboration, the foregoing will so fully explain my invention that others may, 20 by applying current knowledge, readily adapt the same for use under various conditions of service.

I claim:

1. A device of the type described comprising two grip parts, one of said grip parts including a 25 trough, one end of the other part being arranged to lie within the trough, and means for detachably connecting the two grip parts for holding said one end in pinching relation with said trough, each of said grip parts being provided 30 with slots for connection with a garter, the slot in the grip part having the trough being positioned lower than the other slot when the grip parts are fastened together.

2. A garter fastening comprising a first grip 35 part having an abutment, a second grip part having an end co-operating with said abutment for pinching a stocking, means for detachably connecting said parts, said end of the second grip part being held in pressure relation with said 40 abutment when the two parts are fastened together, and means movably connecting said parts together, said second means being connected with the two parts in such a manner as to transfer the pull on the fastening to one of said parts 45 when the two parts are connected together.

3. A garter fastening comprising a first grip part having an abutment, a second grip part having an end cooperating with said abutment for pinching a stocking, means for detachably connecting said first and second grip parts, said 50 means holding said second part in stocking pressure relation with said abutment, said first and second parts being slotted, and a supporting strap passing through said slots, the slot in said 55 first part being lower than the slot in the second part when the parts are connected, to transmit the load on said strap to said first part.
